TOOTHPICK DEVICES

Mario Petitta, New York, N.Y.

Application January 23, 1958, Serial No. 710,779

1 Claim. (Cl. 132—89)

The present invention is an improvement in the art 15 relating to toothpicks.

The principal object of this invention is to provide a novel implement presenting an extending quill for toothpick use. This quill is formed of the end of a flat ribbon which is of Celluloid, plastic, bristol board or other resilient paper-thin material; such implement serving as the 20 toothpick handle, the former to bend the tape into a toothpick handle, the former to bend the tape into a duct-form, as hereinafter described and preferably as the holder of a compact supply of the ribbon stock.

Another object thereof is to provide a novel toothpick device of the character mentioned, accomplishing automatic duct formation of the end region of the initially flat ribbon, so that a used toothpick point can be cut off and a new one made, thus affording a new toothpick 30 for use at approximately every three-quarter inch or so of the ribbon supply.

A further object of this invention is to provide a novel and improved toothpick device of the kind set forth, which is simple in construction, easy to use, reasonably cheap to manufacture, relatively small in size and efficient for the 35 purposes it is designed.

Other objects and advantages will become apparent as this disclosure proceeds.

For the practice of this invention, one form it may assume comprises a holder having a roll of the flat ribbon and a tubular member through which the ribbon lies and extends therefrom, say for about three quarters of an inch. Such extending free end of the ribbon which is 40 out of the forward end of the tubular member, is cut with a scissors to be in the form of an unslit pen point. The forward end of said tubular member is round and its rear end is flattened. The opening in the rear end is a narrow elongated slot admitting the ribbon in flat condition. The diameter of the opening in the forward end of said tubular member is approximately between a third and a half of the width of the ribbon. The ribbon through the tubular member will be automatically formed and extend forwardly thereof in duct form. Depending upon the size of the forward opening, the extending formed part of the ribbon will be a duct which is tubular, a tube-form with a longitudinal opening or a longitudinal channel-form, the free end of which is then cut by the user to quill-form. If desired, a removable cap may be provided to shield the exposed quill to maintain it in sanitary condition and the holder for the ribbon supply may be an openable casing. The entire device may be of plastic, metal or other suitable material, but the ribbon must be paper-thin and have some resilient quality.

In the accompanying drawings forming part of this specification, similar characters of reference indicate corresponding parts in all the views.

Fig. 1 is a lengthwise view of a toothpick device embodying the teachings of this invention. The ribbon supply holder is here shown in open condition and a removable shielding cap encasing the toothpick quill is here included. Such cap is here shown in section.

2

Fig. 2 is a top plan view of Fig. 1 minus the shielding cap. The ribbon supply holder is shown closed.

Fig. 3 is a perspective view showing the tubular member. The ribbon is shown dash and dot.

5 Fig. 4 is an enlarged section taken at lines 4—4 in

Fig. 3.

Fig. 5 is an enlarged section taken at lines 5—5 in Fig. 3.

10 Fig. 6 is an enlarged section taken as is Fig. 5, but of modified form.

Fig. 7 shows a lengthwise view of the tubular member with the free end portion of the ribbon therethrough. At the entrance into the rear opening of said member, the ribbon is flat. The forwardly extending free end of the ribbon which is out of the tubular member, is of duct-form.

In the drawing, the numeral 15 designates generally a preferred form of the toothpick device. As shown, it consists of a tubular member 16 positioned on a holder for a supply of ribbon stock. Such holder may be a casing 17 having a hinged cover 18. The ribbon supply is preferably a roll thereof indicated as 19. The free end portion of the ribbon 19' is threaded through said tubular member and extends outwardly therefrom, say about three-quarters of an inch to an inch, as at "A." The intake opening 20 of this tubular member is communicative with the interior of the casing 17 in the embodiment shown. This intake opening is a narrow slot of a size to admit the ribbon 19' in flat condition. In fact, the rearward portion 21 of the tubular member has its interior so dimensioned that the ribbon remains flat therein. The forward portion may be circular as at 22, or square as at 23, or any other suitable shape to accomplish forming of the ribbon therethrough into duct-form. If circular or square, the distance across the forward opening of the tubular member 16, is less than the width of the ribbon, and preferably from about one-third to one-half thereof, so that the ribbon will be of duct-form along distance "B"; the intermediate portion of the tubular member 16, having an interior which smoothly merges the interiors of the portions 21 and 22. The tubular member 16 can be formed by flattening one end of a piece of suitable tubular stock.

45 For use, a scissors is employed to trim the extended part 24 along C—C so that the quill-form is made, meaning the form of an unslit pen point and thus serve as a toothpick. After once used, the pointed free end of the ribbon is pulled out and a new point cut. It is evident 50 that the ribbon supply will afford a multiplicity of toothpicks for successive use.

To keep the fresh point clean until used, a cap or 55 thimble 25 may be provided to shield it. This cap is of course removable from its frictional hold on the step 26' 55 of the collar 26 which is carried on the tubular member 16. The tubular member aforesaid, the collar 26 and the ribbon supply holder 17 comprise a unitary structure. The ribbon supply when spent, is then replenished. It is evident that the entire article is quite small and can 60 be easily carried in a lady's hand bag or in a man's vest pocket.

The article described can be decoratively embellished and the ribbon stock may be of colored material.

65 This invention is capable of various forms and applications without departing from the essential features herein disclosed. It is therefore intended and desired that the embodiments shown herein shall be deemed merely illustrative and not restrictive and that the patent shall cover 70 all patentable novelty herein set forth; reference being had to the following claim rather than to the specific description herein to indicate the scope of this invention.

I claim:

In a toothpick device of the character described, a comparatively short tubular member having open ends and a comparatively long, initially flat ribbon of paper thin material having some resilient quality and having a pointed free end; the end portion of said ribbon having such pointed end, being positioned through said tubular member and extending outwardly a predetermined distance from one end opening of said tubular member; the second end opening of said tubular member being of a size and shape admitting said ribbon in flat condition; the distance across the first end opening of said tubular member being less than the width of the ribbon whereby the longitudinal edges of the ribbon are brought towards one another whereupon said outwardly extending end part of the ribbon is formed into a lengthwise quill adapted for use as a toothpick; the interior space of said tubular member comprising three successive regions; the

interior space region ending with the first end opening of the tubular member, having the cross-section of said first end opening; the interior space region ending with the second end opening of the tubular member, having the cross-section of said second end opening; the interior surface of the portion of the wall of the tubular member which determines the intermediate space region within said tubular member, merging smoothly with the interior surfaces of the portions of the wall of said tubular member, which determine the other interior space regions.
